(57) **CLAIM**

The ornamental design for a table base as shown and described.

DESCRIPTION

FIG. 1 is a front, top, right-side perspective view showing my new design;

FIG. 2 is rear top, right-side perspective view thereof;

FIG. 3 is rear top, left-side perspective view thereof;

FIG. 4 is front top, left-side perspective view thereof;

FIG. 5 is a top plan view thereof;

FIG. 6 is a bottom plan view thereof;

FIG. 7 is a right-side view thereof;

FIG. 8 is a left-side view thereof;

FIG. 9 is a front view thereof;

FIG. 10 is a rear view thereof; and,

FIG. 11 is a front, top, right-side perspective view thereof, shown in an environment of use with a tabletop. The broken lines showing a tabletop form no part of the claimed design.
